UNITED STATES PATENT OFFICE

ALLEN DE VILBISS, JR., OF TOLEDO, OHIO, ASSIGNOR TO TOLEDO COMPUTING SCALE COMPANY, OF TOLEDO, OHIO, A CORPORATION OF NEW JERSEY.

DESIGN FOR A COMPUTING-SCALE HOUSING.

40,593.

Specification for Design.

Patented Mar. 29, 1910.

Application filed December 16, 1909. Serial No. 533,484. Term of patent 14 years.

To all whom it may concern:

Be it known that I, ALLEN DE VILBISS, Jr., a citizen of the United States, residing at Toledo, in the county of Lucas and State of Ohio, have invented a new, original, and ornamental Design for Computing-Scale Housings, of which the following is a specification, reference being had to the accompanying drawing, forming part thereof.

The figure is a perspective view of a com-

puting scale housing, showing my new design.

I claim:

The ornamental design for a computing scale housing, as shown.

ALLEN DE VILBISS, JR.
